Primary Examiner — Wan Laymon*Assistant Examiner* — Clint A Samuel(74) *Attorney, Agent, or Firm* — Lucian Wayne Beavers;
Patterson Intellectual Property Law, PC(57) **CLAIM**

What is claimed is the ornamental design for a lamp, as shown and described.

DESCRIPTION

FIG. 1 is a first perspective view of the lamp from the left side and from above.

FIG. 2 is a second perspective view of the lamp of FIG. 1, from the right side and from below.

FIG. 3 is a left side elevation view of the lamp of FIG. 1.

FIG. 4 is a right side elevation view of the lamp of FIG. 1.

FIG. 5 is a rear elevation view of the lamp of FIG. 1.

FIG. 6 is a front elevation view of the lamp of FIG. 1.

FIG. 7 is a top view of the lamp of FIG. 1.

FIG. 8 is a bottom view of the lamp of FIG. 1.

FIG. 9 is a left side elevation view of the lamp of FIG. 1 similar to FIG. 3, but with the lamp in a revised configuration as compared to the view of FIG. 3.

FIG. 10 is a left side elevation view of the lamp of FIG. 1 similar to FIG. 3, but with the lamp in a further revised configuration as compared to the view of FIG. 3; and,

FIG. 11 is a left side elevation view of the lamp of FIG. 1 similar to FIG. 3, but with the lamp in a still further revised configuration as compared to the view of FIG. 3.
